(57) **CLAIM**

The ornamental design for a game controller grip, as shown and described.

DESCRIPTION

FIG. 1 is a rear perspective view of a game controller grip showing our new design with a region for enlargement; FIG. 2 is a front perspective view thereof; FIG. 3 is a bottom view thereof; FIG. 4 is a front view thereof; FIG. 5 is a rear view thereof; FIG. 6 is a left side view thereof; FIG. 7 is a right side view thereof; FIG. 8 is a top view thereof; and, FIG. 9 is an enlarged view of the region identified by the label “FIG. 9” shown in FIG. 1.

The broken line showing of the remainder of the game controller in FIGS. 1-8 is for environmental purposes only and forms no part of the claimed design. The broken line “FIG. 9” label, the uneven length broken line, and the curved broken lead line shown in FIG. 1 form no part of the claimed design.
